FOREIGN PATENT DOCUMENTS

GB 762869 12/1956

Primary Examiner — Abraham Bahta(74) *Attorney, Agent, or Firm* — Richard O. Bartz(57) **CLAIM**

The ornamental design for a kneeler platform, as shown and described.

DESCRIPTION

FIG. 1 is a top plan view of a first embodiment of the kneeler platform showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a sectional view taken along line 7-7 of FIG. 2;

FIG. 8 is an enlarged sectional view taken along line 8-8 of FIG. 7;

FIG. 9 is a top plan view of a second embodiment of the kneeler platform showing my new design;

FIG. 10 is a front elevational view of FIG. 9;

FIG. 11 is a rear elevational view of FIG. 9;

FIG. 12 is a left side elevational view of FIG. 9;

FIG. 13 is a right side elevational view of FIG. 9; and,

FIG. 14 is a bottom plan view of FIG. 9.

1 Claim, 7 Drawing Sheets(56)
